(57) **CLAIM**

The ornamental design for a laser scanner, as shown and described.

DESCRIPTION

FIG. 1 is a top perspective view of a laser scanner, showing our new design;

FIG. 2 is a bottom perspective view of the laser scanner shown in FIG. 1;

FIG. 3 is a front view of the laser scanner shown in FIG. 1, the rear view being a mirror image thereof;

FIG. 4 is a side view of the laser scanner shown in FIG. 1; FIG. 5 is another side view of the laser scanner shown in FIG. 1;

FIG. 6 is a top view of the laser scanner shown in FIG. 1; and,

FIG. 7 is a bottom view of the laser scanner shown in FIG. 1.

The broken lines in the drawings illustrate portions of the laser scanner that form no part of the claimed design.
